[57] CLAIM

The ornamental design for a bottle, as shown and described.

DESCRIPTION

FIG. 1 is a front elevation of a bottle showing my new design, the rear elevation is the same;

FIG. 2 shows a right side elevation thereof with the left side view being a mirror image thereof;

FIG. 3 shows a top plan view thereof; and,

FIG. 4 shows a bottom view thereof.

The broken lines showing a bottle neck are for illustrative purposes only and do not form part of the claimed design.
